(57) **CLAIM**

The ornamental design for an electrical cord connector apparatus, as shown.

DESCRIPTION

FIG. 1 is a perspective view of an electrical cord connector apparatus;

FIG. 2 is a front view thereof;

FIG. 3 is a back view thereof;

FIG. 4 is a side view thereof (opposite side is mirror image);

FIG. 5 is a top view thereof; and,

FIG. 6 is a bottom view thereof.

The broken lines shown in the drawings are included for the purpose of illustrating environmental structure and form no part of the claimed design.
